UNITED STATES PATENT OFFICE.

CHARLES W. LEDIG, OF PHILADELPHIA, PENNSYLVANIA.

DESIGN FOR A CANTEEN.

SPECIFICATION forming part of Design No. 19,050, dated April 16, 1889.

Application filed January 5, 1889. Serial No. 295,568. Term of patent 3½ years.

To all whom it may concern:

Be it known that I, CHARLES W. LEDIG, a citizen of the United States, residing in the city and county of Philadelphia, State of Pennsylvania, have invented and produced a new and original Design for a Canteen, of which the following is a specification, reference being had to the accompanying drawings, forming part thereof.

10 The leading feature of my design for a canteen is a shield with a star or stars, a bead inclosing the same, and a monogram of interlaced letters within said shield.

In the drawings, in which Figure 1 represents the obverse and Fig. 2 the reverse, to 15 which reference is made, A designates a canteen having on opposite sides the beads B C.

Within the bead B is a monogram of fanciful interlaced letters. Within the bead C is a shield, E, on which is a star, G, and within 20 which is a monogram, F, of fanciful interlaced letters.

Having thus described my invention, what I claim as new, and desire to secure by Letters Patent, is—

25 A design for a canteen having a shield with a star, a bead inclosing said shield, and a monogram of interlaced letters within the same, as shown and described.

CHARLES W. LEDIG.
